Oliver Davidson, of Ballston Spa, New York.

Letter of Patent.

The Schedule referred to in these Letters Patent, and making part of the same, containing a description in the words of the said Oliver Davidson, himself of his improvement in an apparatus for closing doors is as follows.

To all to whom these presents shall come, Be it known that I Oliver Davidson, of Ballston Spa, County of Saratoga and State of New York, have invented a new and useful improvement for the purpose of closing doors, as set forth, and that the following is a full and exact description of the construction and operation of the said improvement, as invented and improved by me, viz. It consists of a compound lever placed in the door casement and connected with the door by a cord or chain. This lever is composed of two bars or rods of iron, each from ten to twelve inches in length united by a rule joint, the angle or inclination which bars to each other is limited by fixtures in the casement and by a chord to not less than forty-five degrees. The lower extremity of the lever is fastened in the casement upon a pivot, which forms a fulcrum and permits the requisite motion. The other extremity is forked and has placed in a weight which is intended to run in the manner of a batter, on the inner surface of the basement, the cord or chain is attached to the lever below the joint, and passing over a pulley in the basement is connected with the door by a staple whose the door is opened the cord draws the lever towards a straight line the weight moving up, but when the power applied is withdrawn the weight descends bringing back the lever to its first position and thereby closing the door. An interior view of this apparatus is given in the annexed drawing. A. is the compound lever fastened with its lower extremity b. on a pivot in the casement. C. is the weight or batter which passes down on the inner surface of the door basement. The chord (d) fastened at one end on lower arm of the

line, and at the other in a straight line. (b) The upper parts are also seen in the second drawing (a), the lower arm of the lever with its pivot which is to be fastened in the easement (b), the plate in the easement in which the pivot is inserted. (c) The weight or counter (d) the upper arm of the lever forked for the admission of the counter. The application of power by this mechanical construction for the purposes within specified is new and I claim to be the inventor.
